CLAIM

The ornamental design for a skipper ball, as shown and described.

DESCRIPTION

FIG. 1 is a perspective, environmental view of the skipper ball, depicting the skipper ball attached to a hose;

FIG. 2 is a front elevational view of the skipper ball shown in FIG. 1;

FIG. 3 is a left side elevational view of the skipper ball shown in FIG. 1;

FIG. 4 is a right side elevational view of the skipper ball shown in FIG. 1;

FIG. 5 is a rear elevational view of the skipper ball shown in FIG. 1;

FIG. 6 is a top plan view of the skipper ball shown in FIG. 1; and,

FIG. 7 is a bottom plan view of the skipper ball shown in FIG. 1.

Surface shading or stippling is included in the drawings to show the character and contour of the surfaces of the three dimensional aspects of the skipper ball or to show contrasting surfaces unlimited by colors.

The features illustrated in evenly-spaced dashed lines are included for illustrative purposes only to depict the environment of the skipper ball and form no part of the claimed design.
